BAG FORMING, HANDLING, AND FILLING
MECHANISMHans Irmischer, New York, N. Y., assignor to Millie
Patent Holding Co. Inc., New York, N. Y., a
corporation of New York

Application May 8, 1933, Serial No. 669,943

6 Claims. (Cl. 226—59)

The present invention relates to bag forming, handling and filling mechanism and embodies, more specifically, an improved mechanism by means of which portions of material open at the ends thereof, are directed over and held by suitable supporting mechanism by means of which the material is moved through a sewing machine to sew one end thereof to form a receptacle. This receptacle is subsequently supported by the supporting mechanism in an open position to facilitate the filling thereof.

In this connection it is old to form receptacles by severing portions from a continuous sleeve of material and supporting the severed portions upon suitable arms by means of which the severed portions are moved under a sewing machine to sew one end of the portions. Such mechanism is shown and described in the copending application of Louis Hirschhorn and Hans Irmischer for Cloth feeding mechanism for combination tea bag machine, Serial No. 614,090, filed May 28, 1932. In order that the receptacles which have previously been formed in the manner shown and described in the above identified co-pending application may be filled while engaged by the aforesaid supporting means, the present invention has been designed and an object of this invention, accordingly, is to provide a bag forming and filling mechanism by means of which bags or receptacles may be formed and filled while mounted upon a common supporting means.

A further object of the invention is to provide a bag or receptacle forming and filling means whereby one end of a sleeve of material is sewed with over-locked stitching to form a receptacle, the receptacle being subsequently supported in an open position for filling thereof.

A further object of the invention is to provide a bag forming and filling mechanism by means of which sleeves of material are supported upon arms which move one end of the sleeves through a sewing machine to form a receptacle thereof and subsequently open the mouths of the receptacles without impressing upon the receptacles injurious stresses or strains.

A further object of the invention is to provide supporting means for receptacles by means of which the sides of the receptacles adjacent the mouths thereof may be supported in either spaced apart relationship or juxtaposed relationship without tending to vary the length of the material constituting the mouths of the receptacles.

A further object of the invention is to provide a bag forming and supporting mechanism by

means of which portions of material are moved through a sewing machine to form receptacles thereof, the supporting means subsequently holding the mouths of the receptacles in open position whereby the same may be filled. After such filling operation, the supporting means is actuated to release the receptacles at a predetermined station.

Further objects, not specifically enumerated above, will be apparent as the invention is described in greater detail in connection with the accompanying drawings, wherein:

Figure 1 is a plan view showing a bag forming and filling mechanism by means of which portions of a continuous sleeve are applied to supporting arms and subsequently moved through a sewing machine to form receptacles thereof, after which they are supported in an open position to be filled and released.

Figure 2 is a partial view in side elevation showing the bag or receptacle supporting mechanism with a receptacle over the arms thereof after the same has passed through a sewing machine to stitch one end thereof.

Figure 3 is a view in section, taken on line 3—3 of Figure 2 and looking in the direction of the arrows, this view showing the manner in which a receptacle is supported over the arms of the device prior to reaching a filling mechanism.

Figure 4 is a view similar to Figure 3, showing the position of the bag supporting arms when the arms have been moved into a position such that a filling operation may be effected. This position of the arms and receptacle is such as illustrated at the lower portion of Figure 1.

Figure 5 is an enlarged plan view of a portion of the supporting wheel structure including the supporting arms and operating mechanism therefor.

Figure 6 is a detail view showing the mechanism by means of which a substance is introduced into an open receptacle.

Referring to the above drawings, a supporting wheel or carrier is shown at 10 and is provided with a plurality of mounting surfaces 11 upon which receptacle supporting arms may be mounted as described hereinafter. The wheel 10 is rotatably mounted upon a spindle 12 supported by a suitable stationary structure 13 and rotated intermittently in the direction of the arrow of Figure 1 by any suitable mechanism.

Upon each of the supporting surfaces 11, pairs of brackets 14 and 15 are journaled by means of pins 16 and 17, respectively. Each bracket 55

14 and 15 is provided with an extension 18 within which a vertical shaft 19 is journaled. The shafts 19 are formed with broad flat bag engaging and supporting arms 20 upon which bags 5 or receptacles may be placed from below by the attendant.

Bracket 14 is formed with an arm 21 at the end of which are formed teeth 22. Bracket 15 is formed with an arm 23 at the end of which 10 is formed a tooth 24 which is adapted to lie between the teeth 22 on arm 21. A stop pin 25 limits movement of the arms 21 and 23 downwardly as viewed in Figure 2 and, in this fashion, simultaneous, swinging movement of the 15 arms 20 toward and away from each other on horizontal axes is effected simultaneously. The shafts 19 extend upwardly through the extensions 18 and terminate in notched portions 26 between which a coil spring 27 extends. Spring 27 thus 20 normally urges arms 20 apart and places a desired tension upon the receptacle which has been placed over such arms. An extension 28 is formed on one of the brackets (in the present construction, bracket 15) and this arm is adapted 25 to be engaged by either of two cams 29 and 30 (Figure 1) whereby movement of the cams into engagement with the extensions 28 effects movement of the arms 20 toward each other to enable a receptacle to be released from the arms 30 20 or to be readily moved thereover.

The broad, flat arms 20 which may thus be swung toward and from each other on horizontal axes may also be rotated about their own vertical axes through 90° to cause the same to lie 35 in the same plane or in parallel planes, as shown in Figures 3 and 4. The mechanism for controlling such movement is illustrated in Figures 2 and 5, wherein each shaft 19 has secured thereto an arm 31. A link 32 connects the arms 31 40 and a spring 33 is secured to the link at 34 and to the bracket 15 at 35. In this fashion, the arms 20 are normally urged into a position illustrated in dotted lines in Figure 5 and in full lines in Figure 4, wherein they lie in parallel planes. 45 One of the arms 31 is formed with an extension 36 upon which a roller 37 is journaled. This roller is adapted to engage a segmental cam rail 38 to maintain the bag supporting arms 20 in the position shown in Figures 2 and 3. In such 50 position the wheel 10 advances the material from a station at which portions thereof are applied to the supporting arms 20, through a sewing machine which preferably sews one end of each of the portions with overcast stitching as indicated 55 at 39. After such operation, the roller 37 rides off of the cam rail 38 and the bag supporting arms 20 are moved into the position illustrated in Figure 4 and by dotted lines in Figure 5. In this position, the receptacles are filled by means 60 of a filling mechanism. The filling mechanism 40 may be mounted upon an arm 41 which is formed upon the base of the machine 13 and includes spaced vertical guide rods 42 upon which a head 43 is slidably mounted (Figure 6). A 65 link 44 is connected between the head 43 and an extension 45 of the cam 29. In this fashion, movement of the head 43 takes place in accordance with movement of the cam 29. A filling spout, 46 is secured to the head 43 and, upon 70 downward movement thereof, is moved downwardly into the dotted position shown in Figure 6. The lower end of the filling spout in such position lies within the open mouth of the receptacle which is held in open position by the 75 arms 20. At this time, a suitable substance may

be directed into the receptacle through the filling spout, after which filling operation the spout 46 is elevated into a position above the path of movement of the arms 20. The downward movement of cam 29, subsequent to the filling operation performed by the filling spout 46, engages extension 28 and moves arms 20 together to release the receptacle which was supported thereover. In Figures 2, 3, 4, and 6, a receptacle 47 has been shown as mounted over the arms 20. 10 Upon movement of the arms 20 toward each other as previously described, the receptacle falls upon a transfer table or turret 48 and is supported in a vertical position by means of arms 49. This structure may follow any of the common structures now in use for transferring the receptacle to a closing apparatus and in as much as it forms no part of the present invention will not be described in further detail herein. 15

From the foregoing, it will be seen that a forming and filling apparatus has been provided by means of which portions of material which have been previously folded and sewed along an edge parallel to the fold are applied to supporting arms by means of which the lengths are fed through 20 a sewing machine to close one end thereof. The sewing operation preferably applies overcast stitching to the one end and thus provides a receptacle which is sufficiently attractive in appearance, thus avoiding the necessity of turning the same inside out prior to filling. After this sewing operation, the receptacles are moved into a filling position and, without being removed from the supporting arms, are filled and discharged into a receiving apparatus. The particular form of supporting arms and the operating mechanism therefor enables the receptacles to be formed while in a substantially flat condition and subsequently opened without applying injurious strains to the fabric of the receptacles whereby the receptacles may be filled 30 while being supported upon the supporting arms. 35

While the invention has been described with specific reference to the accompanying drawings, it is not to be limited, save as defined in the 45 appended claims.

I claim as my invention:

1. Bag handling means comprising a movable carrier, broad, flat, bag supporting arms mounted on the carrier and adapted to enter a bag and present it for subsequent operation, means to swing the arms toward each other to facilitate the placing of the bag thereupon and the discharge of the bag therefrom, and means to rotate the arms on their longitudinal axes to place them in parallel planes and thereby hold the bag in open position. 50

2. Bag handling means comprising a movable carrier, broad, flat, bag supporting arms mounted on the carrier and adapted to enter a bag and present it for subsequent operation, means to swing the arms toward each other to facilitate the placing of the bag thereupon and the discharge of the bag therefrom, means to rotate the arms on their longitudinal axes to place them in parallel planes and thereby hold the bag 55 in open position, and means to fill the opened bag. 60

3. Bag handling means comprising a movable carrier, broad, flat, bag supporting arms mounted on the carrier and adapted to enter a bag and present it for subsequent operation, means to swing the arms toward each other to facilitate the placing of the bag therefrom, means 70 to

to rotate the arms on their longitudinal axes to place them in parallel planes and thereby hold the bag in open position, means to fill the opened bag, and means to release the filled bag from the 5 supporting arms.

4. Bag handling means comprising a movable carrier, broad, flat, bag supporting arms mounted on the carrier and adapted to enter a bag and present it for subsequent operation, means to 0 swing said arms toward each other to facilitate the placing of the bag thereon and the discharge of the bag therefrom, means to rotate the arms 5 on their longitudinal axes to place them in parallel planes and thereby hold the bag in open position, means to fill the bag, and a single means to move the filling means into filling position and also subsequently to actuate the supporting arms to release the filled bag.

5. Bag handling means comprising a movable carrier, broad, flat, spaced, bag supporting arms on the carrier, means to move the arms toward each other to facilitate the reception of a bag thereon, and means to rotate the arms upon their longitudinal axes to place them in parallel planes and thereby hold the bag in open position. 5

6. Bag handling means comprising a movable carrier, broad, flat, spaced arms to receive a bag mounted on the carrier on horizontal axes and 10 also mounted to rotate on vertical axes, means to swing the arms toward and from each other on the horizontal axes, and means to rotate the arms on their vertical axes to place them in 15 parallel planes and thereby hold the bag in open position.

HANS IRMSCHER.
